UNITED STATES PATENT OFFICE.

HARRY E. CAMPBELL, OF NEW YORK, N. Y.

SASH-SUSPENSION DEVICE.

1,171,168.

Specification of Letters Patent.

Patented Feb. 8, 1916.

Application filed December 16, 1915. Serial No. 67,295.

To all whom it may concern:

Be it known that I, HARRY E. CAMPBELL, a citizen of the United States, residing at New York, in the county of New York and State of New York, have invented a certain new and useful Improvement in Sash-Suspension Devices, of which the following is a specification.

The invention relates to sash suspension devices.

Where suspension shafts carrying sprocket or chain wheels fast on each end, over which wheels the sash chains pass, are to be introduced into hollow lintels, wherein said shafts have their journal bearings, difficulty is found in assembling the shafts in the lintels after the window-frame has been built in place. This is chiefly due to the necessarily restricted area of the opening in the bottom of the lintel through which each shaft with its affixed wheels must be inserted. My present invention is designed to overcome this difficulty, and consists in the construction of the hollow lintel and the suspension shafts and wheels adapted thereto, as more particularly hereinafter set forth.

In the accompanying drawings—Figure 1 is a vertical longitudinal section of my improved sash suspension device on the line 1, 1 of Fig. 2. Fig. 2 is a horizontal section on the line 2, 2 of Fig. 4. Fig. 3 is a bottom view. Fig. 4 is a cross section on the line 4, 4 of Fig. 1. Fig. 5 is a cross section on the line 5, 5 of Fig. 1. Fig. 6 shows one of the chain wheels, and shaft support therein, the stirrup and the cover of said support in perspective and separated.

Similar letters and numbers of reference indicate like parts.

A is the hollow box-shaped lintel of a window-frame. Wall B at each end and a plate C forming part of the bottom wall are formed integrally. The top wall D and side walls E are formed integrally of a suitably bent metal plate which rests upon the end walls. On the end walls B are lugs F which receive the bolts G, by which the lintel is secured to the sill, not shown. The bottom plates C rest upon the jambs H, which are hollow to receive the suspension counterweights I. The opening in the bottom of the lintel is closed by a metal plate J resting against shoulders K, Fig. 1, in the inner edges of the plates C, and secured by bolts L entering angle-bars M on the side walls E.

Preferably integrally formed with the bottom plates C are upwardly projecting blocks N, with concavities to receive the ball-bearings O for the journals P of the chain wheels 7. Said journals may be formed integrally with said wheels. On the opposite side of each wheel, and also preferably formed integrally therewith, is a supporting seat 8 for the shaft 9, which is of polygonal cross section so as to fit and be seated in said support. The shaft is united to said support by a stirrup 10 which passes under said seat 8. The threaded ends of the stirrup pass through openings in the cover 11, which fits upon the shaft, and are secured by nuts.

There are two parallel shafts 9, having supports and chain wheels at their ends, as described. Over each wheel passes a chain 12, having one end secured to a sash partly shown in Fig. 4 at 13, and the other end to a counter-weight I. The chains 12 pass through suitable openings in the bottom plates C. The wheels 7 are disposed in recesses in the blocks N.

By reason of this construction the introduction of the suspension shafts and wheels into the hollow lintel, after the window-frame is built in place, is greatly facilitated. To this end the cover plate J is removed, and the wheels having been passed through the bottom opening, are seated in the bearings in blocks N. The shafts can then be placed in their seats 8, and the cover plates 11 are finally introduced and secured in place.

I claim:

1. A sash suspension device, comprising a polygonal shaft, two chain wheels, bearings for said wheels, sash chains engaging said wheels, polygonal seats for said shaft extending from opposing faces of said wheels, and means for securing said shaft in said seats.

2. A sash suspension device, comprising a polygonal shaft, two chain wheels, bearings for said wheels, sash chains engaging said wheels, polygonal seats for said shaft extending from opposing faces of said wheels, a stirrup receiving said seat, and a cover fitting upon said shaft and engaging the legs of said stirrup.

3. A sash suspension device, comprising a polygonal shaft, a hollow lintel having an opening in its bottom wall, two parallel chain wheels having journals projecting

from their outer faces, fixed bearings in said
lintel receiving said journals, sash chains
engaging said wheels, polygonal seats for
said shaft extending from the opposing
5 faces of said wheels, and means for secur-
ing said shaft in said seats.

In testimony whereof I have affixed my
signature in presence of two witnesses.

HARRY E. CAMPBELL.
